(57) **CLAIM**

The ornamental design for multi-sized offset handle tongue and groove pliers, as shown and described.

DESCRIPTION

FIG. 1 is a perspective view of the first embodiment of my design.

FIG. 2 is a front view thereof.

FIG. 3 is a rear view thereof.

FIG. 4 is the top plan view thereof.

FIG. 5 is a left side elevational view thereof; the left side elevational views of embodiments 2 and 3 being identical to this view.

FIG. 6 is a bottom view thereof.

FIG. 7 is a right side elevational view thereof; the right side elevational views of embodiments 2 and 3 being identical to this view.

FIG. 8 is a perspective view of the second embodiment of my design.

FIG. 9 is a front view of this second embodiment.

FIG. 10 is a rear view thereof.

FIG. 11 is a top plan view thereof.

FIG. 12 is a bottom plan view thereof.

FIG. 13 is a perspective view of the third embodiment of my design.

FIG. 14 is a front elevational view thereof.

FIG. 15 is a rear view thereof.

FIG. 16 is a top plan view thereof.

FIG. 17 is a bottom plan view thereof.

FIG. 18 is a perspective view of the fourth embodiment of my design.

FIG. 19 is a front view thereof.

FIG. 20 is a rear view thereof.

FIG. 21 is a top plan view of the right hand version of the first embodiment.

FIG. 22 is a left side elevational view thereof; the left side elevational views of embodiments 5 and 6 being identical to this view.

FIG. 23 is a bottom view thereof.

FIG. 24 is a right side elevational view thereof; the right side elevational views of embodiments 5 and 6 being identical to this view.

FIG. 25 is a perspective view of the fifth embodiment of my design.

FIG. 26 is a front view thereof.

FIG. 27 is a rear view thereof.

FIG. 28 is a top plan view thereof.

FIG. 29 is a bottom plan view thereof.

FIG. 30 is a perspective view of the sixth embodiment of my design.

FIG. 31 is a front elevational view thereof.

FIG. 32 is a rear view thereof.

FIG. 33 is a top plan view thereof; and,

FIG. 34 is a bottom plan view thereof.

FIGS. 1–17 depict views of left hand user tools of this design, while FIGS. 18–34 depict views of right hand user tools of this design.

The broken lines in the drawings illustrate unclaimed portions of the pliers and form no part of the claimed design.
